APPARATUS FOR BURNING PULVERIZED FUEL

Haskell C. Carter, Portland, Oreg., assignor to
Iron Fireman Manufacturing Company, Port-
land, Oreg.

Application December 18, 1934, Serial No. 758,051

1 Claim. (Cl. 110—28)

This invention relates generally to heat generating devices, and particularly to an apparatus for burning pulverized fuel.

The main object of this invention is the provision of an improved form of apparatus for burning powdered fuel in which the products of combustion are freed from practically all solids before being liberated to the atmosphere.

The second object is the construction of a special form of furnace for use in the practice of the invention.

These, and other objects, will become more apparent from the specification following as illustrated in the accompanying drawing, in which:

15 Fig. 1 is a plan of the device.

Fig. 2 is an elevation with a portion of the furnace broken away in section.

Fig. 3 is a section taken along the line 3—3 in Fig. 2.

20 Similar numbers of reference refer to similar parts throughout the views.

Before entering into a description of this invention it will be understood that devices for burning powdered fuel have long been in use. It is therefore not my intention to cover such devices broadly, my improvement relating generally to the combination of a burner for powdered fuel with an exhaust fan which serves as a separator for moving the solids from the gases.

30 It must also be understood that with an apparatus of this kind the burning fuel travels at a relatively high velocity and therefore its path of travel must be extended far beyond the distance available in the ordinary type of furnace, in order 35 to provide ample time for the combustion to take place and the heat contained in the fuel to be given up to the conveying medium.

Referring in detail to the drawing, there is shown a furnace 10 which, in this instance, is of the hot water type and is covered by means of an insulating jacket 11. In the bottom 12 is formed a cylindrical well 13 in which is formed the retort 14 of refractory material.

The retort 14 is preferably in the form of a cone through whose central opening 15 extends the pipe 16 which supplies fuel and air to the nozzle 17. The gas pipe 18 is provided to supply gas to the pilot burner 18—A which extends into the retort 14. A damper 19 is placed within the opening 15 around the pipe 16 and is controlled by the manually operated rod 20. Air enters the opening 15 through the tunnel 21 from the perforated floor plate 22.

Over the well 13 is secured a conical shell 23 which constitutes the fire box. To the upper end

of the shell 23 is connected a return bend 24 which is joined by a vertical pipe 25 to a second return bend 26 which is connected by a riser pipe 26—A to the top 27 of the furnace. The pipe 26—A is connected by an elbow 28 and the horizontal pipe 29 to an exhaust fan 30 of the type which includes a separator for removing the solids therefrom, an example of which is shown in United States Patent Number 1,941,449.

The solids from this fan are discharged through a pipe 31 into a hopper 32 from which they are removed in any convenient manner, such as by withdrawing same into an ash box 33 disposed beneath the hopper 32. A suitable motor 34 is provided to drive the exhaust fan 30.

15 The furnace 10 is provided with a clean-out opening 35 which communicates with the interior of the shell 23 and is closed by means of a door 36. The usual water connections 37 and 38 are indicated, although they form no part of the 20 present invention; same being equally applicable to warm air furnaces.

In order to supply powdered fuel to the pipe 16 there is provided a crusher 39 which is operated by a motor 40, or may be operated from the same 25 prime mover as is the fan 30 without departing from the spirit of this invention. Fuel is delivered to the crusher 39 from the hopper 31 by gravity.

The operation of the device is as follows: As- 30 suming that the motors 34 and 40 are being operated, it follows that the fan 30 will reduce the pressure within the fire box 23 causing the air to flow through the pipe 16 into the fire box, drawing with it powdered fuel which is being delivered by 35 the crusher 39. The correct proportion between the amount of fuel and air delivered is obtained by regulating the damper 19. The particles of fuel which float into the fire box 23 are ignited by 40 the pilot burner 18—A and are fully consumed before they have traveled the entire length of the conduits 24 to 26—A.

Obviously, the number of pipes 26 and 26—A can be increased for the purpose of further elongating the distance traveled by the gases before 45 escaping from the furnace, without departing from the spirit of this invention.

It can be seen from the foregoing that there is provided a system of burning powdered fuel which 50 will overcome the conditions usually accompanying such installations, and, moreover, due to the velocity of the gases passing through the furnace, there will be set up a scouring action which will keep the interior of the gas conducting conduits 55

clean and enable them to transmit the liberated heat to the water or other medium which surrounds the elements 23 to 26—A.

In an apparatus of this type a chimney will be almost unnecessary since no stack draft is required as the gases discharged from the fan outlet 42 are practically free from all solids since these have been trapped out into the hopper 32, and the combustion within the fire box 23 has been so complete that there is practically no smoke passing from the furnace.

It is desirable to provide a control valve 43 in the pipe 18 in order that the state of combustion and the ratio between the air and fuel delivered 15 may be better controlled.

I claim:

In an apparatus for burning powdered fuel, the combination of a firebox having an elongated combustion chamber associated therewith, an exhaust fan for drawing the products of combustion from the combustion chamber whereby the pressure within the combustion chamber may be reduced below that of the surrounding atmosphere and a powdered fuel feeder open to the atmosphere on one side and discharging into said firebox on the opposite side whereby powdered fuel may be drawn into said firebox by the same fan which removes the products of combustion therefrom. 5 10
